UNITED STATES PATENT OFFICE.

LLOYD G. COPEMAN, OF FLINT, MICHIGAN, ASSIGNOR OF ONE-HALF TO JOHN F. BURLESON, OF GRAND RAPIDS, MIGHIGAN.

COLLAPSIBLE GREASE-CAPSULE.

1,190,382.

Specification of Letters Patent. Patented July 11, 1916.

Application filed September 10, 1915. Serial No. 49,933.

To all whom it may concern:

Be it known that I, LLOYD G. COPEMAN, a citizen of the United States, residing at Flint, county of Genesee, State of Michigan, have invented a certain new and useful Improvement in Collapsible Grease-Capsules; and declare the following to be a full, clear, and exact description of the same, such as will enable others skilled in the art to which it pertains to make and use the same, reference being had to the accompanying drawings, which form a part of this specification.

This invention relates to a collapsible grease-capsule in combination with a grease-cup to lubricate moving parts of a machine.

Heretofore it has been customary to use the conventional form of grease-cup by filling the same with hard grease with the aid of a knife or other tool. It has been found a rather disagreeable job to fill a grease-cup in this way as it requires not only time but it is difficult to put the grease in the cup without some of it being left on the sides and without distributing the grease in places where it is undesirable and sometimes getting it on the hands. I do away with these inconveniences and difficulties by employing a paper grease-capsule in which the hard grease may be packed and sold. These capsules may be placed in the conventional grease-cup that are so designed that they will collapse without in any way interfering with the discharge of the grease. This will more fully appear in the description following.

In the drawings, Figure 1 is a view of the open end of the capsule. Fig. 2 is a longitudinal section of the capsule. Fig. 3 is a view of the disassembled grease-cup and capsule, largely in section. Fig. 4 is a view of the same parts assembled partly in section. Fig. 5 is a similar view showing the follower of the grease-cup advanced and the grease-capsule collapsed.

45 a designates the cylinder of a conventional grease-cup which is provided with a screw-threaded nozzle b through which the grease is forced and which may be screwed into one of the parts to be lubricated. The 50 opposite end of the cylinder is threaded at c to receive the screw-threaded cap d into which runs the threaded screw e which is provided with a follower f.

The capsule is designated g and comprises a cylindrical shell of paper closed at one 55 end and open at the other. This capsule is so constructed that when subjected to pressure on its closed end it will collapse in the manner shown in Fig. 5, that is to say, in a large number of bellows-like folds. It is 60 very material that the grease-capsule collapse with a large number of bellows-like folds or otherwise it might collapse in such a way as to have the folds practically trap the grease in the cup so that it would not 65 be forced through the passage-way in the nozzle.

From the above description it will be seen that the grease can be packed in the grease-capsules and sold to the trade in this shape, 70 and the user may then merely insert the capsule in the grease-cup by removing the cap d and placing the grease-cup with the open end toward the nozzle. When the cap d is screwed back on the cylinder, the follower f may be advanced by turning the screw e. The grease will be forced out of the nozzle in the quantities proportional to the advance of the follower. When the grease-capsule has been completely collapsed, the cap and follower may be removed and the collapsed grease-capsule pulled out by the use of any sharp-pointed tool.

What I claim is:

The combination with a grease-cup, having a bottom portion provided with a relatively small discharge opening, of a collapsible capsule located within the grease-cup, a part of the bottom portion of the 90 grease-cup being formed and arranged to furnish a perpendicular abutment for the end of the collapsible capsule, the said capsule having a relatively large open inner end of substantially greater area than the 95 discharge opening of the grease-cup so as to span said opening and bear against the perpendicular abutment at a point remotely related to the discharge opening of the grease-cup, and means for collapsing the 100 capsule upon the abutment, substantially as described.

In testimony whereof, I sign this specification.

LLOYD G. COPEMAN.
